CLAIM

The ornamental design for a medical patch, as shown and described,

DESCRIPTION

The patent or application file contains at least one drawing executed in color. Copies of this patent or patent application publication with color drawing(s) will be provided by the Office upon request and payment of the necessary fee.

FIG. 1 is a front view of a medical patch of the present invention.

FIG. 2 is a rear view of the medical patch of FIG. 1.

FIG. 3 is a top plan view of the medical patch of FIG. 1.

FIG. 4 is a bottom view of the medical patch of FIG. 1.

FIG. 5 is a right side view of the medical patch of FIG. 1.

FIG. 6 is a left side view of the medical patch of FIG. 1.

FIG. 7 is a perspective view with a part of the coversheet peeled off of the medical patch of FIG. 1.

FIG. 8 is a reference view showing the pattern of the coversheet of the medical patch of FIG. 1; and,

FIG. 9 is a reference front view without the pattern of the medical patch of FIG. 1 in use.
